UNITED STATES PATENT OFFICE.

FREDERICK G. DADMUN, OF MONTREAL, QUEBEC, CANADA.

BELT CUTTING AND PUNCHING TOOL.

Application filed June 22, 1923. Serial No. 647,055.

To all whom it may concern:

Be it known that I, FREDERICK G. DADMUN, a citizen of the United States of America, residing at 344 Notre Dame Street 5 west, in the city of Montreal, in the Province of Quebec, in the Dominion of Canada, have invented certain new and useful Improvements in Belt Cutting and Punching Tools; and I do hereby declare that the following is a true, clear, and exact description 10 of the same.

This invention relates to the class of cutting and punching tools particularly designed for working on the round belting 15 commonly used on sewing machines, etc.

The main object of the invention is to provide a simple, strong, and most economical tool that will easily and readily effect the neat cutting of the ends of the belt and 20 the correct piercing of the holes for the ordinary wire fasteners whose ends have to be bent over the belt ends when such belts are being repaired.

To assemble or repair a belt of this character, first the ends require to be neatly cut off for a variable distance. The next operation consists in punching a hole, perfectly centered through the belt, at a fixed distance from each end; and, after inserting the wire 25 fastener through these holes, the ends of the fastener are then bent over and plied on the belt. To execute these operations properly, generally requires some skill, particularly for the neat adjustment of the ends of the 30 belt in accordance with the distance at which the holes are punched to conform with the size of the wire fastener. Also, care must be taken for punching the holes perfectly 35 through the center of the belt, for the proper alinement and wear of the belt.

This tool will perform the various operations in a most satisfactory manner, even in the hands of unskilled persons; and its mode of operation and structural details, together with its general advantages, will be 40 hereinafter fully described.

In the accompanying drawings:

Figure 1 represents a form of the invention comprising a pair of cutting and punching elements,

Fig. 2 shows a modification,

Fig. 3 is an edge view of the tool showing it as being used in carrying out the cutting and wire fastening operations,

Fig. 4 is a detail view of the one-piece cutting and punching element, and

Fig. 5 is a fragmental view of a fastened belt.

Like numerals of reference indicate corresponding parts in each figure.

In appearance, the tool is constructed somewhat like an ordinary pair of pliers, comprising likewise jaws 1 and handles 2 pivoted at 3 in cross-lever relation, said handles having enlarged portions or jaw members 1^a. Almost in line with the pivot 3 and at right angles with each jaw 1, is a projecting portion 4 slotted between its faces to receive the pivot end of the cutting and punching member 5, which is carried in a channel 5^a formed between the faces of the enlarged portions or jaw members 1^a of the handles. The channel 5^a and the slot in the projecting portion 4 are, of course, disposed in alinement, so as to permit the above-described arrangement of the member 5. The thickness of the tool is preferably equal to double the distance of the hole to be punched from the end of the belt; hence, the face of the tool will serve as a guide for the 80 punching operation.

The cutting and punching member 5 is preferably formed in one integral piece and consists of a pivoting bar terminating at its outer end in a T-shaped portion. The leg 85 of the T forms the cutter 6 and has its edge sharpened at right angles with one arm of the T, which arm extends immediately under the pivoting bar and parallel thereto and forms the punch 7. The other or rearwardly 90 extending arm 8 of the T acts as a guide for the member 5, and is retained in the channel of the handle 2 by a pin 9 against which the upper edge of this arm bears, while the member 5 is allowed to move longitudinally 95 with the handle 2.

Through the thickness of the tool, and directly in the respective paths of the punch 7 and cutter 6, are two holes 10 and 11 through which the belt is inserted for its 100 respective operation.

It is evident that, as represented in Fig. 1, the two halves of the tool (the upper and lower as shown) may be alike; or that, as illustrated in Fig. 2, only the upper half 105 may have the structural features described.

In Fig. 3, the belt 11^a is shown as inserted through the hole 11 to be cut. The amount to be cut off is necessarily left to the judgment of the operator who may guide 110 said belt at will through the said hole 11. After the belt has been cut, it is then in-

serted through the hole 10, and in closing the tool the belt will be neatly punched.

In the faces of the jaws 1 are grooves 12 forming a circle when the jaws 1 are closed. After the belt has been punched, a wire fastener 12^a is inserted through the punched hole, and the end of the fastener 12^a is then bent over and pressed upon the belt after being placed in between the 10 grooves 12 (see Fig. 3). The jaws 1 have also an elongated nose for the purpose of undoing wire fasteners and for other handy uses in repairing belts of the kind in question.

15 In a tool, as illustrated in Fig. 1, it would be preferable to drill the holes 10 of different diameters. Only few sizes of belts of this nature are in common use, and a tool of this character would, therefore, be of the highest efficiency. Some belts, after being used for a time under certain conditions, lose their consistency and yet are serviceable; hence, the punching operation could be carried out in the hole 10 25 nearest in diameter to that of the belt, which would naturally eliminate most of the deformities.

What I claim as my invention is:—

1. An implement, comprising a pair of 30 levers pivoted together in crossed relation and provided at their rear ends with handles and at their front ends with coacting jaws, and a tool pivoted at its front end to the jaw of one lever and extending rearwardly into a longitudinal channel in the other lever to move endwise in said channel during the opening and closing of the handles; the rear portion of the tool embodying a working member which operates 35 in the channel when the handles are being closed.

2. An implement according to claim 1, in which the tool embodies a front stem portion and a T-shaped rear portion, the latter portion being disposed in the channel and comprising a guide member and at least one working member.

3. An implement according to claim 1, in which the tool embodies a front stem portion and a T-shaped rear portion, the latter portion being disposed wholly within the channel and comprising a punch, a cutter, and a guide.

4. An implement according to claim 1, in which the tool embodies a front stem portion and a T-shaped rear portion, one arm of the T forming a punch and the other arm forming a guide, and the leg of the T forming a cutter.

5. An implement according to claim 1, in

which the rear portion of the tool embodies a member for guiding the tool during its endwise movements and at least one working member.

6. An implement according to claim 1, in which the rear portion of the tool embodies a member for guiding the tool during its endwise movements and at least one working member, and in which the channeled lever has a cross-pin extending through the 70 channel for engagement with the guide member, and also has an opening formed through it which intersects said channel transversely and across which the working member moves during its operation. 75

7. An implement, comprising a pair of levers pivoted together in crossed relation and provided at their rear ends with handles and at their front ends with coacting jaws; one lever having an enlargement at the inner end of its handle which is formed along its outer edge with a longitudinal channel, and the other lever having a projection adjacent and at right angles to its jaw which is formed with a slot alining 85 with the channel; and a tool pivoted at its front end in said slot and extending rearwardly into said channel to move longitudinally therein when the handles are opened and closed, the rear portion of the tool 90 having a working member which operates in the channel during the closing of the handles.

8. An implement, comprising a pair of levers pivoted together in crossed relation 95 and provided at their rear ends with handles and at their front ends with coacting jaws; one lever having an enlargement at the inner end of its handle which is formed along its outer edge with a longitudinal 100 channel, and the other lever having a projection adjacent and at right angles to its jaw which is formed with a slot alining with the channel; a tool pivoted at its front end in said slot and extending rearwardly into said channel to move longitudinally 105 therein when the handles are opened and closed, the rear portion of the tool having a guide member and a working member, the latter of which operates in the channel 110 during the closing of the handles, and a cross-pin extending through said channel for sliding engagement with the guide member.

Signed at Montreal, Quebec, Canada, this 115 8th day of June, 1923.

FREDERICK G. DADMUN.
